CARL WILH. GROSS, OF BRIDGEPORT, CONNECTICUT, ASSIGNOR TO GROSS AND STEINER, OF BRIDGEPORT, CONNECTICUT, A COPARTNERSHIP CONSISTING OF CARL W. GROSS AND VICTOR A. STEINER.

CAN OPENER.

1,426,182.

Specification of Letters Patent. Patented Aug. 15, 1922.

Application filed March 7, 1921. Serial No. 450,332.

To all whom it may concern:

Be it known that CARL W. GROSS, a citizen of Germany, and resident of Bridgeport, in the county of Fairfield and State of Connecticut, has invented certain new and useful Improvements in Can Openers, of which the following is a specification.

This invention relates to an improved can opener of the type adapted to remove an end from the body portion of a can by circumferentially cutting through the wall of the can adjacent the end to be removed.

The invention has for its principal object to provide a novel device of the present character, of simple construction and consisting of few parts, which can be fastened upon a support to be quickly and easily manipulable by use of one hand, the operator's other hand being free to grasp the can when the novel device shall have performed its work.

A further important object is to provide a can opener equipped with a feeding roller adapted to engage the inner side of the flange of a can, with a rotatable gripping roller adapted to be clamped against the outer side of said flange in opposed relation to the feeding roller and carrying a circular cutter, having a cutting edge adapted to pierce the wall of the can adjacent said flange when the rotatable gripping roller is clamped against said flange, and with mechanism whereby the rotatable gripping roller may be so clamped and the feeding roller may be rotated to advance the can against the cutting edge of the circular cutter in order that said cutting edge may continuously cut through the can wall for its full circumference.

A still further important object is to provide in the device a rotatable gripping roller that will be normally free to move from and toward the feeding roller, and to so construct and arrange the rotatable gripping roller and the mechanism for rotating the feeding roller that said mechanism can be readily manipulated to remove the rotatable gripping roller from the flange of a can when this is desirable, as well as to clamp the same against said flange.

With the above and other objects in view, the invention comprises the construction, arrangement and combination of parts as now

to be fully described and hereinafter specifically claimed.

In the accompanying drawing forming a part of this specification, wherein like numerals of reference designate corresponding parts,

Fig. 1 is a top plan view of the can opener, showing the rotatable gripping roller located closely adjacent the feeding roller;

Fig. 2 is a bottom plan view, showing the rotatable gripping roller spaced its farthest distance from the feeding roller;

Fig. 3 is a side elevational view, showing the rollers positioned as in Fig. 2;

Fig. 4 is a view, on an enlarged scale, of the side of the can opener opposite that shown in Fig. 3, disclosing the rollers positioned as in Fig. 1 and a can as when being opened;

Fig. 5 is an enlarged sectional view on line 5—5 in Fig. 3, looking in the direction of the arrows; and

Fig. 6 is an enlarged sectional view on line 6—6 in Fig. 3, looking in the direction of the arrows.

Referring to the drawing, 10 denotes a plate adapted to be fastened upon a support as by means of a clamp (not shown) or by the utilization of screw holes 11. Secured upon plate 10 and spaced therefrom, as by means of pins 12, is a disc plate 13, a portion of which, designated by 14, projects beyond plate 10 for a purpose to be explained, and extending through plates 10 and 13 are duplicate, aligning cam slots, designated by 15, preferably of about the configuration shown. A stud 16, passing through the cam slots to ride and rotate therein and extending upwardly beyond plate 13 as denoted by 17, rigidly carries a rotatable gripping roller 18 and a circular cutter 19 having a cutting edge 20 located adjacent the rotatable gripping roller, said gripping roller and circular cutter being snugly arranged between plates 10 and 13 to hold the stud in upright position and to ride and rotate therewith, as will be understood.

Projecting portion 14 of plate 13 has a bearing block 21 fixed thereon, and a short shaft 22, rotatably mounted in the bearing block and in portion 14, carries upon its lower end a preferably serrated feeding roller 23 adapted to lie closely adjacent the

under face of the disc plate, and upon the upper end of the short shaft is fixed an operating lever 24 for the purpose of rotating the feeding roller, the inner end of the 5 operating lever, as very clearly disclosed, resting upon the top surface of the bearing block. Numeral 25 denotes a set screw for holding the lever upon the short shaft in usual manner, and 26 denotes a metal washer 10 between the head of the set screw and the operating lever.

A cam member 27 upon the under side of the operating lever and secured thereto in any manner, as by ordinary screws 28, is 15 provided with a cam face 29 adapted to engage stud 16, when the operating lever is rotated in the direction of the arrows in Figs. 1 and 2 and the stud is located as in Fig. 2, to move said stud to about the position shown in full lines in Fig. 1. Numeral 30 denotes a guide pin which may be situated upon the under side of disc plate 13 and adjacent the feeding roller to assist the feeding roller in guiding a can A when being cut, see particularly Fig. 4, and 31 denotes an ordinary form of handle which may be arranged upon the outer end of the operating lever.

The device operates in the following manner: When it is desired to open a can, the rotatable gripping roller is first moved away from the feeding roller to be situated as shown in Figs. 2 and 3 or as suggested by dotted lines in Fig. 1, and an end of a can 30 is next positioned against the under face of disc plate 13 so that the inner side of the flange of the can is in engagement with or closely adjacent the feeding roller and guide pin. See Fig. 4. The operating lever is 35 then rotated, in the direction of the arrows in Figs. 1 and 2, until the end of the can is removed. Referring more particularly to Fig. 1 and to the dotted line positions of the operating lever and stud therein, upon 40 the initial rotation of the operating lever, cam face 29 rides against portion 17 of the stud and moves it to about the position in which it is shown in full lines in said figure, as will be understood, to cause the cutting edge of the circular cutter to pierce the can and the rotatable gripping roller to be 45 clamped against the outer side of the flange of the can in opposed relation to the feeding roller. Continued rotation of the operating 50 lever and feeding roller, obviously, will cause the gripping roller, together with the circular cutter, to rotate and will feed the can forwardly against the cutting edge of the circular cutter. It will be evident that 55 the stud cannot at this time be removed from the position in which it is shown in full lines in Fig. 1, for the reason that the rotating force exerted against the gripping roller is in a direction toward that end of 60 the duplicate cam slots in which said stud

is arranged. When the end of the can has been removed from the body portion thereof, the flange can be released from the rollers by simply reversely turning the operating lever for a short distance, say, for example, 70 from its full line position in Fig. 1 to or toward its dotted line position in said figure. The effect of the reverse turn is to feed the flange backwardly against the gripping roller to cause stud 16 to ride backwardly in the 75 cam slots, to or toward the dotted line position of the stud in Fig. 1, and the rotatable gripping roller to be moved away from the feeding roller to allow another can to be opened in the manner already fully set 80 forth.

It is to be remarked that the can opener of this invention is capable of opening cans of any cross-sectional configuration.

While I have shown and described one 85 specific embodiment of the invention, it is to be understood that such changes in details of construction and arrangement of parts may be made as fall within the spirit of the invention and within the scope of the 90 appended claims.

Having thus fully described the invention, what I claim as new and desire to secure by Letters Patent is:

1. In a can opener, a pair of spaced apart 95 upper and lower plates having duplicate, aligning slots, and can opening means associated with said plates.

2. In a can opener, a pair of spaced apart upper and lower plates having duplicate, 100 aligning slots, a stud adapted to ride in said slots, said stud extending upwardly beyond said upper plate, a gripping roller upon said stud and between said plates, a feeding roller carried by said upper plate, 105 a cutter associated with one of the rollers, means for rotating the feeding roller, and a device upon said means adapted to engage said stud to move one of said rollers toward the other of said rollers. 110

3. In a can opener, a pair of spaced apart plates having duplicate, aligning slots, a stud in said slots and extending beyond one of said plates, a roller upon said stud and between said plates, a roller carried by one 115 of said plates, a cutter associated with one of said rollers, means for rotating the rollers and cutter, and a device carried by said means adapted to engage said stud to move said rollers toward each other. 120

4. In a can opener, a pair of spaced apart upper and lower plates having duplicate, aligning slots, a stud adapted to ride in said slots, said stud extending upwardly beyond said upper plate, a gripping roller 125 upon said stud and between said plates, a short shaft mounted in said upper plate and carrying a feed roller, a cutter associated with one of said rollers, and unitary means for rotating the feeding roller and 130

for moving said rollers toward each other.

5. In a can opener, a pair of spaced apart plates having duplicate, aligning slots, a stud adapted to ride in said slots, said stud extending beyond one of said plates, a roller upon said stud and between said plates, a roller carried by one of said plates, a cutter associated with one of said rollers, and unitary means for rotating said rollers and for 10 moving said rollers toward each other.

6. In a can opener, a pair of spaced apart plates having duplicate, aligning slots, a stud adapted to ride and rotate in said slots, said stud extending beyond one of said plates, a rotatable gripping roller upon said stud and between said plates, said gripping roller adapted to slide between said plates, a rotatable feeding roller upon one of said plates, a cutter associated with one of said 15 rollers, means for rotating the feeding roller, and a device upon said means adapted to engage said stud to move the gripping roller toward the feeding roller.

7. In a can opener, a pair of spaced apart plates having duplicate, aligning slots, a stud adapted to ride in said slots, said stud extending beyond one of said plates, a gripping roller upon said stud and between said plates, a feeding roller carried by one 20 of said plates, a cutter associated with one of said rollers, a member for rotating said rollers, said member carrying a device adapted to engage one of said rollers to move the same toward the other of said 25 rollers when the member is rotated to feed a can, the device being capable of moving

the rollers apart when the member is rotated in opposite direction.

8. A can opener comprising a pair of spaced apart upper and lower plates having 40 duplicate, aligning slots, a stud adapted to ride and rotate in said slots, said stud extending upwardly beyond said upper plate, a gripping roller and cutting edge upon said stud and between said plates, a short 45 shaft mounted in said upper plate and carrying a feeding roller, means for rotating said shaft, and a cam face upon said means adapted to engage said stud to move said gripping roller toward said feeding 50 roller.

9. A can opener comprising a pair of spaced apart upper and lower plates having duplicate, aligning slots, a stud adapted to ride and rotate in said slots, said stud extending upwardly beyond said upper plate, 55 a rotatable gripping roller and cutting edge upon said stud and between said plates, said gripping roller adapted to slide between said plates, a bearing block upon said upper plate, a short shaft mounted in said bearing block and upper plate, a feeding roller carried by said shaft, a lever for rotating said shaft, and a cam face upon said lever adapted to engage said stud to move 60 said gripping roller toward said feeding 65 roller.

Signed at Bridgeport, in the county of Fairfield, and State of Connecticut, this 4th day of March, A. D., 1921.

CARL WILH. GROSS.
